DESIGN FOR FABRIC.

SPECIFICATION forming part of Design No. 33,570, dated November 13, 1900.

Application filed October 11, 1900. Serial No. 32,792. Term of patent 7 years.

To all whom it may concern:

Be it known that I, WILLIAM H. FLETCHER, a citizen of the United States, residing at Paterson, in the county of Passaic and State of New Jersey, have invented and produced a new and original Design for Fabrics, known as "Fancy Velours," of which the following is a specification, reference being had to the accompanying drawing, forming a part thereof, which is a plan view showing the design.

The leading or material features of my design for fabrics are the parallel stripes A, which are each composed of side borders a a' , provided with dentiform reentrant points b b' .

The points b b' alternate and are uniformly 15 spaced apart. Between the fancy stripes A are arranged the plain stripes B.

What I claim is—

The design for a fabric known as "fancy velour," substantially as shown and described.

In testimony that I claim the foregoing as my invention I have signed my name in presence of two subscribing witnesses.

WILLIAM H. FLETCHER.
